United States Patent

Des. 242,238
Patented Nov. 9, 1976

242,238

FOLDABLE MOTOR SCOOTER

Orland W. Richardson, Columbus, Ohio, assignor to
Joseph Skilken & Co., Columbus, Ohio

Filed Dec. 1, 1975, Ser. No. 636,647

Term of patent 14 years

Int. Cl. D12—11

U.S. Cl. D12—110

FIG 1

FIG 2

FIG. 3

FIG. 4

FIG. 5

FIG. 6

FIG. 1 is a right side elevational view of a foldable motor scooter;

FIG. 2 is a left side elevational view thereof;

FIG. 3 is a top plan view thereof;

FIG. 4 is a front elevational view thereof;

FIG. 5 is a rear elevational view thereof; and

FIG. 6 is a side elevational view thereof in its folded condition.

I claim:

The ornamental design for a foldable motor scooter, as shown.
